(57) CLAIM

The ornamental design for a border edging, as shown and described.

DESCRIPTION

FIG. 1 is a front elevational view of the border edging of the invention, the opposite side being substantially a mirror image thereof;

FIG. 2 is a top plan view of the border edging of FIG. 1;
FIG. 3 is a right side view of the border edging of FIG. 1;
FIG. 4 is a left side view of the border edging of FIG. 1; and,
FIG. 5 is a bottom plan view of the border edging of FIG. 1.
